UNITED STATES PATENT OFFICE.

EMIL KREUSER, OF MECHERNICH, GERMANY.

ELECTROMAGNETIC APPARATUS FOR SEPARATING ORES.

SPECIFICATION forming part of Letters Patent No. 639,062, dated December 12, 1899.

Original application filed February 28, 1899, Serial No. 707,212. Divided and this application filed May 12, 1899, Serial No. 716,608. (No model.)

To all whom it may concern:

Be it known that I, EMIL KREUSER, retired director of Royal Mines, a citizen of Germany, residing at Mechernich, Rhine Province, Germany, have invented certain new and useful Improvements in Electromagnetic Apparatus for Separating Ores, (for which I have made application for a patent in Great Britain, dated February 8, 1899, No. 2,849,) of which the following is a specification.

This invention relates to a construction of electromagnetic ore-separators described in the specification to my application for a patent, filed February 28, 1899, Serial No. 707,212, in which two revolving bar electromagnets with polar surfaces of cylindrical form and having the wire coils wound on parts of reduced diameter situated between the poles are arranged with their polar surfaces of different polarity placed opposite each other. According to the present improvements such electromagnets are made with at least three polar surfaces, with intermediate wire coils so wound that by the electric current passed through the same the two outer or end poles of the magnet receive the same polarity, while the middle or intermediate pole is of opposite polarity, the poles of the one magnet being, however, as before, of the opposite polarity to those of the other magnet which are presented to them, so that between the two is formed a series of fields of great intensity. A considerably-varied action of the magnets can be obtained with this arrangement by making the cylindrical poles of either one or both magnets of different diameters instead of making them of equal diameters, as heretofore. The diameters of the two outer poles can either be made smaller or larger than that of the middle pole. In the first-named case the intermediate poles of the electromagnets in being put in direct metallic contact with each other form a pair of contact-poles and do not serve for separating the ore, but for regulating the polar distance between two outer pairs of poles which serve for the separation of the ore. The distance between these cylindrical polar surfaces will depend upon the relative proportion between

their diameter and that of the pair of contact-poles. In the second above-named arrangement, in which the two outer poles of each magnet have a greater diameter than the intermediate poles, only the latter are employed for the separation of the ores, while the outer poles serve as pairs of contact-poles, which regulate the distance between the intermediate poles. The contact-poles also serve for transmitting the rotary motion which is imparted to the one electromagnet from the outside to the other one, as owing to the magnetic action the contact-poles attract and are consequently pressed strongly against each other, so that if the one magnet be rotated the resulting strong frictional contact will cause the second one to be carried around with it. In both the above-described arrangements the diameters of the two cylindrical poles that are opposite each other can be made different, so that by this means the two cylinder magnets can be made to revolve at different speeds. The distance between the poles that effect the ore separation can be varied in two different ways. On the one hand the contact-poles can be made variable in diameter by fitting upon them iron rings of different thicknesses, and on the other hand the contact-poles may have the form of conical frusta. In this latter case the distance between the ore-separating poles can be varied by shifting the magnets longitudinally relatively to each other.

The above-described arrangements for making some of the cylindrical poles serve as contact-poles, while the other or others serve as ore-separating poles, are not limited to a construction of magnets with three poles. The magnets can be constructed with any desired number of such poles, pairs of which are made to serve either as contact-poles or as ore-separating poles. Also it is not necessary that both the cylinders should be provided with wire coils for rendering them magnetic, as one of them can be without winding and made to serve as a cylindrical armature, becoming more or less magnetic by the magnetic induction from the electromagnet.

The above-described improved construc-

tion offers the following advantages: With this arrangement special devices for regulating the distance apart of the ore-separating poles are rendered unnecessary, as such regulation is effected, as described, by the contact-poles. Furthermore, the magnetic resistance of the apparatus is much less than with existing constructions, as in place of two air-resistances there is in each magnetic circuit only one air-resistance to be overcome by the magnetic lines of force, inasmuch as at the contact-poles the transmission of the magnetic lines of force takes place directly from metal to metal.

15 In the accompanying drawings, illustrating my invention, Figure 1 is a detail side elevation of two cylindrical electromagnets with one pair of contact-poles embodying my invention. Figs. 2 to 9, inclusive, are similar views showing modifications or variations hereinafter explained in detail, and Fig. 10 is a side elevation of a magnetic ore-separator embodying my invention.

15 In Fig. 1, A and B are the middle or intermediate cylindrical poles which are of enlarged diameter, so as to serve as contact-poles, while C D and E F are the two pairs of cylindrical poles, which serve as ore-separating poles. G, H, I, and K are the wire coils 20 wound on the reduced intermediate parts of the magnets, to which the electric currents are supplied through the sliding contact-rings a, b, c, and d. The coils are wound in such manner that on the passage of electric currents through them, as indicated, for example, by the arrows, the outer poles C D are rendered of south polarity, while the intermediate pole A is rendered of north polarity, the outer pole E F being, on the other hand, rendered north, while B is rendered south. The dotted lines indicate the circuit of the magnetic flux through the two magnets. Both magnets are revolvable upon their axes e g and f h, and on imparting rotary motion to the one 30 magnet after they have been magnetized by the passage of a current such motion is transmitted to the second one by the strong frictional contact between the contact-poles A B, produced by their magnetic attraction.

45 Fig. 2 shows the same construction as at Fig. 1, but with the outer poles C' D' E' F' made to constitute the contact-poles, while the intermediate poles A' B' constitute the ore-separating poles.

50 Figs. 3 and 4 show two arrangements in which the opposite poles of the two magnets are of unequal diameters. In Fig. 3 the intermediate poles A² B² are the contact-poles, as at Fig. 1, A² being smaller than B², so that 55 the upper magnet will revolve at a quicker speed than the lower one, which arrangement is of advantage in many cases. In Fig. 4 the outer poles are the contact-poles, as at Fig. 2,

those of the upper magnet C² D² being greater than E² F², so that the lower magnet revolves 65 faster than the upper one.

Fig. 5 shows a part elevation and part longitudinal section, and Fig. 6 an end view, of a modification in which the magnets are each provided with five poles, the two outer 70 pairs being the contact-poles, while the three intermediate pairs are the ore-separating poles.

The rings m n o p, fitted on the contact-poles, are also of soft iron and are arranged 75 so that they can be changed for the purpose of varying the polar distance between the ore-separating poles, as above described.

Figs. 7 and 8 show two modifications of the second above-described arrangement for regulating the polar distance. In Fig. 7 the intermediate pair of poles A³ B³ are the contact-poles, these being made as conical frusta, so that on shifting the one magnet longitudinally relatively to the second one the polar 85 distance will be either increased or decreased. In Fig. 8 the two outer pairs of poles are the contact-poles and are formed as conical frusta. Fig. 9 shows the above-described arrangement, in which only the upper cylinder 90 is provided with wire coils, so as to constitute an electromagnet, the lower one serving as armature and being only rendered magnetic by induction.

Fig. 10 shows an elevation of a magnetic 95 ore-separator in which the cylindrical magnets are of the type shown in Fig. 7. The axes e g and f h revolve in bearings i j and k l, respectively fixed to the framing L. The sliding contact-rings a b c d are keyed to the 100 axes on which they are mounted, respectively, and are insulated therefrom, while the brushes q r s t convey the current for exciting the magnets. The lower cylinder is revolved by means of the gearing P and drives the upper 105 cylinder through the contact-poles A B of the magnets, such as are shown in Fig. 7.

Having thus particularly described and ascertained the nature of this invention and the best means I know for carrying the same into 110 practical effect, I claim—

1. In an electromagnetic ore-separator, a pair of cylindrical electromagnets having at least three cylindrical poles of larger diameter than the intermediate parts on which the 115 wire coils are wound, the two end poles being of the same polarity while the intermediate pole is of opposite polarity, and one of the sets of poles being made of larger diameter than the other so that such larger poles of 120 one magnet are in contact with those of the other, while the polar distance between the smaller poles constitutes the magnetic field for the separation of the ores, substantially as described.

2. In an electromagnetic ore-separator, the

combination of a pair of cylindrical electro-
magnets having at least three poles one or
more of the poles of the one magnet being in
contact with one or more poles of the other
magnet, while the other poles have a space
between them which constitutes the magnetic
field for the separation of the ores, and means
for varying the diameters of the poles that
are in contact, in order to vary the polar dis-
5

tance between the other poles, substantially 10
as described.

In testimony whereof I have hereunto set
my hand in presence of two subscribing wit-
nesses.

EMIL KREUSER.
